UNITED STATES PATENT OFFICE.

JOHN B. SMITH, OF CHICAGO, ILLINOIS.

STEAM-ENGINE.

SPECIFICATION forming part of Letters Patent No. 291,794, dated January 8, 1884

Application filed June 18, 1883. (No model.)

To all whom it may concern:

Be it known that I, JOHN B. SMITH, a citizen of the United States, residing at Chicago, in the county of Cook and State of Illinois, 5 have invented certain new and useful Improvements in Steam-Engines, of which the following is a specification, to wit:

My invention relates to an improvement in steam-engines; and it consists in certain peculiarities of construction and arrangement, whereby the cylinder is placed very low, the parts are made stronger and more compact, and the connecting-bar between the two pitmen is made self-adjusting, substantially as 15 will be hereinafter more fully set forth.

In order to enable others skilled in the art to which my invention appertains to make and use the same, I will now proceed to describe its construction and operation, referring to the 20 accompanying drawings, in which—

Figure 1 is a front elevation of my engine. Fig. 2 is a longitudinal vertical section. Fig. 3 is a side elevation. Fig. 4 is a section through the cross-head. Fig. 5 is a side elevation of the 25 same. Fig. 6 is a sectional view of one of the cross-head slides. Fig. 7 is a face view of the weighted crank, and Fig. 8 is a side view of the same.

A represents the main casting or cylinder 30 of my engine, which is cast with a steam-chest, A' A², upon each side, as seen in Fig. 2. The chest A' is used for the admission of steam to the cylinder, and the chest A² for the exhaust of the same, and each is fitted with a slide- 35 valve, A³ A⁴. The steam-chest A' is connected at either end by ports a a with the ends of the cylinder, behind the piston, and the valve A³, as it travels back and forth, alternately opens and closes these ports for the admission of 40 steam in the usual manner. The other steam-chest, A², is formed with two cored passages or ports, a' a', which connect the ends of the cylinder with the steam-chest a slight distance from its ends, as represented, and each of these 45 passages is also provided with a small port, a⁵ a⁶, which enters the chest at its ends, for a purpose presently understood. The web of metal which separates the exhaust-steam chest A² from the cylinder is also formed with a 50 passage, a⁷, the ends of which open into the chest near the exhaust-ports a' a', and the face

of the valve A⁴ is provided with two grooves or passages, a⁸ a⁹, which serve to connect the passages a' a³, the latter of which is connected also with the exhaust-pipe A⁵, leading to any 55 desired condenser or to the outer air. The heads of the cylinder A are bolted on, as usual, and it is provided with a piston, B, the rod B' of which extends upward through a suitable stuffing-box, b, of the usual or any of the well-known forms. The whole of the main casting A is secured to or cast with a bed-plate or base, C, in which is journaled the shaft C', formed with a cranked portion, C², outside of which upon one end is the fly-wheel C³, and 65 on the other a driving-pulley, C⁴.

It will be observed that each of the cranks C² is provided with an extension, C⁵, in rear of the crank-arm, which is of sufficient weight to counterbalance the weight of the connecting-rods, equalizing-bar, cross-head, and pitmen, and preserves a more even speed upon the shaft. 70

Upon the top of the casting A are secured four stanchions, D D D D, extending upward 75 a suitable distance, and having their ends provided with vertical arms D', which form guides or ways, in which the sliding cross-head blocks travel. These guides are secured together at their upper and lower ends by 80 metal straps d d, and connected transversely of the engine by similar straps, d' d', the whole forming a substantial and solid but light framework, in which the working parts of the engine are supported or guided. 85

Journalized in boxes d², upon the stanchions D, are two rock-shafts, E, each of which is provided with an arm, E', connected by pitmen E² with the valve-stems E³ E⁴, working the supply and exhaust valves, respectively. 90 These rods move in guides or boxes E⁵ upon the main casting, which boxes are supplied with brasses e e, rendered adjustable for wear by set-screws e' e'.

Upon the outer ends of the rock-shafts E are 95 two similar arms, E⁶, which are connected by rods f f with two eccentrics, F F, upon the shaft C', by means of which the valves are operated at the proper time, as will be readily understood. The upper end of the piston-rod 100 B' is formed with an enlargement or head B², the upper part of which is formed with a

semicircular recess, b' . In this rests the cross-head or equalizing-bar G , which is formed with a semicircular enlargement, g , in its center, and is confined in its place upon the end 5 of the rod B' by means of a corresponding-shaped cap, B^3 , connected to the head B^2 by suitable clip-bolts, b^2 , the whole forming a strong and simple means of connection. The cross-head or equalizing-bar G is tapered from 10 its central enlargement toward each end, where it passes through the slides G' , and has secured upon its ends the pitmen G^2 , connecting it with the cranks C^2 . The slides G' are formed with a recess, g' , in each end, connected by small leads g^2 with the outer or bearing edges, which recesses are to be filled with oil and waste, and form means of keeping the slides and their guides always supplied with a lubricant. The guides are also provided 15 with loose gibbs d^3 , which are adjusted for wear by the set-screws d^4 , as shown. The supply-pipe A^6 is furnished with a globe-valve, a^5 , set close down to the steam-chest, in order that no more steam may be behind the valve than is 20 absolutely necessary, and has also a governor of any desired form. The steam-pipe a^6 leading to the boiler is connected just above the globe-valve, as shown in Fig. 1.

The operation is as follows: Steam being admitted to the chest A' , the piston is driven down to the position shown in Fig. 2, when the valve A^3 is drawn up, shutting off the steam from above and admitting it below the piston to reverse the motion. The exhaust-valve has at the same time been drawn up to close the lower exhaust-passage, a' , at the lower end and make connection between the passages $a' a^3$ to exhaust from the upper end of the cylinder at the same time the small 30 port a^2 , at the lower end of the exhaust-chest, is opened, as shown, to allow of live steam being admitted behind the valve A^4 , in order to keep it properly seated. This operation is reversed when the piston has reached the upper 35 end of its stroke, and is repeated indefinitely. It will be understood that the two valves A^3 A^4 may be adjusted upon their stems to cut off or exhaust at any desired point; and this adjustment is rendered much easier by reason of 40 their being entirely independent of each other. The thrust of the pitmen-rods G^2 is direct in all cases, and should any inequalities of fitting or wear occur the equalizing-bar G will be drawn down at one end, thereby causing both 45 rods to do an equal amount of work, and not place all the strain upon one, as would be the case if this bar were rigidly attached, while at the same time the bar is held perfectly rigid and firm in its socket or boxing. The cylinder 50 is placed immediately over the main shaft, 55

the weight low, and the engine is thereby adapted to high speed, either for stationary or marine purposes.

Having thus fully described my invention, what I claim as new, and desire to secure by Letters Patent, is—

1. In a steam-engine, a piston-rod provided with a boxing upon its outer end, having a circular recess therein opening upon either side, in combination with a cross-head or equalizing-bar, having its center formed to fit the interior of the boxing, and tapered toward either end, substantially as shown and described. 70

2. In a steam-engine, the piston-rod B' , formed with the socketed head B^2 , and provided with a removable cap, B^3 , in combination with the cross-bar or equalizer G , having the semicircular enlargement g , and tapered toward each end, the slides G' and pitmen G^2 connecting it with the cranked driving-shaft, 75

substantially as and for the purpose set forth. 80

3. In a steam-engine, the sliding blocks G' , formed with a recess, g' , in either end, connected to the outer edges by oil-leads g^2 , substantially as and for the purpose set forth. 85

4. In a steam-engine, a steam-chest and valve, for admitting steam to the engine, located on one side of the cylinder, in combination with an exhaust-steam chest upon the opposite side, having small steam-leads connecting the ends of the cylinder, and provided with a slide-valve, adapted to open one of said leads when closing the corresponding exhaust-passage, whereby sufficient live steam is admitted behind the valve to keep it properly seated, substantially as shown and described. 90

5. A steam-engine consisting, essentially, of a cylinder, bed-plate, and two steam-chests, cast in one piece, and placed directly over the driving-shaft, two slide-valves, one for admitting and the other for exhausting the steam, a piston and rod provided with a swivelled equalizing-bar, having slides working in guides supported upon the main casting, and connected by pitmen with the cranked driving-shaft, and two rock-shafts journaled in boxes on the guides and provided with arms connected to the supply and exhaust valves, and operated by eccentrics on the main shaft, all combined, constructed, and arranged to operate substantially as and for the purpose set forth. 100

In testimony whereof I affix my signature in presence of two witnesses.

JOHN B. SMITH.
